UNITED STATES PATENT OFFICE.

GUIDO FORNACA, OF TURIN, ITALY, ASSIGNOR TO F. I. A. T., A CORPORATION OF NEW YORK.

COMBUSTION-ENGINE.

1,190,253.

Specification of Letters Patent.

Patented July 4, 1916.

Application filed January 5, 1911. Serial No. 600,854.

To all whom it may concern:

Be it known that I, GUIDO FORNACA, a subject of the King of Italy, residing at Turin, in the Kingdom of Italy, have invented certain new and useful Improvements in Combustion-Engines, of which the following is a full, clear, and exact specification.

This invention relates to combustion engines and has especial reference to improvements in the construction and arrangement of the parts of a combustion engine, more especially intended for automobiles, whereby the parts will be simplified and rendered more accessible, and also an improved mode of operation secured.

The principal object of the invention is to provide an engine construction wherein exposed moving parts will be entirely eliminated, and external piping and other parts reduced as much as possible thereby protecting the moving parts, rendering the operation of the engine noiseless, and simplifying its external appearance.

The invention has for another object to provide an improved engine construction wherein the cylinders are preferably cast in one block including a water jacket integral therewith, and having improved means for directing and proportioning the circulation of the water to the various cylinders, and also for insuring an equal supply of heated combustible charge to the various cylinders.

The invention with respect to the various parts thereof will be more fully understood in connection with the description of the accompanying drawings, wherein—

Figure 1 is an elevation, seen from the left, of an engine embodying the invention; Fig. 2 is a longitudinal sectional view showing the interior of the engine; the forward half being through the valves, and the rear half being through the cylinders; Fig. 3 is a transverse vertical section through the exhaust valve of the second cylinder from the front; Fig. 4 is an end elevation partly in section showing the arrangement of the various shafts; Fig. 5 is a vertical transverse section through an exhaust valve, on the line 5—5 of Fig. 2, and Fig. 6 is a partial horizontal section through the exhaust pipe, on the line 6—6 of Fig. 3.

1 represents the frame of the machine, 2 the radiator, supported near the bottom by trunnions 3 and flexibly supported at the

top as through the hose coupling 4 leading 55 from the water jacket outlet pipe 5.

6 is the radiator discharge pipe leading to the pump casing 7 formed in the base 30, and discharging by pipe 8 into the lower front portion of the water jacket casing 9. 60 The water enters the water jacket casing in a transverse direction at the lower front portion, and strikes the side of the exhaust pipe 12. This divides the stream, causing one part to pass over the pipe 12 and transversely around and over the front cylinder. The bottom portion of the stream flows transversely under the exhaust pipe 12 and around the lower portions of the cylinders.

At the same time, some of the stream flows 70 longitudinally on the valve side along exhaust pipe 12 (which is spaced from the bottom of the water jacket, as seen in Fig. 3), and consequently, the entire cylinder casting will be equally cooled, including the exhaust 75 pipe 12, the inlet manifold pipe 11, the valve chambers 21, 25, the cylinder heads, etc.

The flow of cool water entering at the bottom divides into parallel streams which flow 80 upwardly over each cylinder and then longitudinally to the single outlet. This flow will be aided by convection, in addition to that due to the force derived from the pump. This prevents strains in the casting by reason of unequal temperatures at various 85 parts. The water flows outward from the casting at the rear end through a port 13 into a passage 14 formed in the removable water jacket cover 15. At the forward end, the cover passage 14 is connected with the 90

radiator inlet pipe 5 in the usual manner. If desired, more than one port 13 may be provided. By this arrangement, the cylinder casting is cooled uniformly and thereby strains avoided, and also external piping is 95 largely eliminated, as but a single short pipe connects the forward end of the casting to the radiator. In order to further direct the flow of water around the various cylinders, including their heads, the inlet pipe 11 and 100 exhaust pipe 12, baffle plates are provided within the jacket, as for instance 17, 18 in Fig. 2, and 19 in Fig. 3, these baffle plates also acting as strengthening ribs between the cylinders and the water jacket. The charge 105 inlet pipe 11 is herein shown as entering the casing on the right hand side at about the middle of the casing, passing between the

second and third cylinders, and thence branching in opposite directions by a passage 20 leading to a double inlet valve chamber 21, containing the inlet valves 22 for the first and second cylinders, and the third and fourth cylinders, respectively. The exhaust valves 24 open from their respective cylinders into exhaust valve chambers 25, which open into the exhaust passage 12 (see Fig. 3), which is surrounded by water space. The utmost compactness in transverse dimension is secured by this arrangement, it being seen that the inlet and exhaust manifolds 20, 12, are below the respective valve chambers 21, 24. Thus the valves practically overhang the inlet and exhaust passages, and the whole casting is thereby very compact and all parts remain at practically the same temperature, owing to the effective 20 and even water circulation to all parts.

From the foregoing description it will be seen that the inlet manifold is so arranged as to cause the charge to be heated by the water jacket before it enters the cylinder, 35 and the common exhaust pipe is also within the water jacket and the exhaust cooled before leaving the engine. It will also be seen that the respective valve chambers are within the water jacket, and that consequently all parts of the cylinders are kept 40 at an equal temperature. This is important in an engine of this type wherein the cylinders are cast in one piece, since otherwise injurious strains would be set up, which 45 might cause breakage. In order to secure this even temperature of all parts of the cylinder, the flow of water to the various cylinders is proportioned, and also directed, so that all parts will receive a proper amount 50 of water from the pump.

The cylinder casting, open at the bottom, is mounted on a base 30, having holes therethrough for the various connecting rods, the base having transverse arms 31 at each end 55 which are fastened to the frame in the usual manner. The crank shaft 32 carries a fly-wheel 33 at the rear end and is mounted to be turned by starting crank 34 to start the engine in the usual manner. The crank shaft is what is known as a three bearing crank shaft; that is, it has a bearing 35 at each end, and an intermediate bearing 36 between the pairs of cylinders, it being understood that the invention is not restricted 60 to a motor having four cylinders, nor to any particular number of bearings. The base 30 is constructed to withstand the strains from the crank shaft and carries complete the bearings 35, and also the other 65 bearings and shafts. In order to protect the crank shaft, a crank case or bottom cover 37 is detachably secured to the bottom of the base as by bolts 370 and this crank case is formed to provide an oil reservoir which 70 can be filled through pipe 38 and from the

bottom of which the oil is taken by pipe 39 to an oil pump 40. (See Fig. 1.) From the oil pipe a suitable oil duct leads through an oil gage 41, and thence through a valve controlled by push pin 42 to the various 75 parts of the engine including the cylinders and the crank shaft bearings. In order to make the external oil ducts as few as possible, and thereby avoid a multiplicity of pipe connections, the base is formed at one side 75 with oil duct 45, which is connected with the bearings 35 and 36 through tubes in the struts 47, at the ends and middle of the base casting. By this arrangement, a proportionate supply of oil is supplied to the various bearings according to the speed of the engine, and also it will be seen that the pistons, crank pins and bearings will be lubricated by the splash from the oil contained in the detachable crank case. 80

The crank shaft 32 carries at its forward end a gear 50, which meshes with a gear 51 splined to the end of cam shaft 52, the gear 51 having a front bearing 53. At the center of the base casting 30 the cam shaft has ordinary bearings 54. Rigid with the cam 52 is a worm pinion 55 which meshes with a similar pinion 56 carried by a transverse shaft 57 (see Figs. 2 and 4), this shaft 57 having a thrust bearing 58 journaled in the 90 forward end of the base casting 30. The gear 51 is twice the diameter of gear 50, so that the cam shaft 52 will be driven at one half of the speed of the crank shaft 32, and the pinion 55 is twice the diameter of pinion 56, so that shaft 57 will be driven at 95 the same speed as the main shaft 32, though of course any other ratio could be employed. 100

60 represents the magneto which is herein shown as mounted on the right forward corner of the base 30 immediately adjacent the forward cylinder, and it is connected to be driven by shaft 57 through a universal or Oldham coupling 61. From the distributor 62 the wires 63 lead to the corresponding spark plugs 64 of the various cylinders, the wires being carried in the conduit 65 supported on the cover 15 or in any other suitable manner. From the engine casting or separate spark plugs the 110 usual return connection to the magneto is provided. The shaft 57, as will be seen from Fig. 4, is supported by webs 66 cast in the base 30, the center web also extending down to support the end bearing 35 for the 115 main shaft, the base being extended to form a cover inclosing the pinions 55, 56. At the opposite end of the shaft 57, there is mounted in a bearing hanger 68, carried by the base 30, a pump shaft 69, connected at 120 one end with the shaft 57 and at the other end having the pump rotor 70 revolving in the pump casing 71. The pump casing 71 is connected with the discharge pipe 6 leading from the radiator and peripherally dis- 130

charges the water into pipe 8, connected as before stated to the water jacket.

It will be seen that an engine constructed according to this invention will have no exposed moving parts, such as gears, cams, valve lifts, etc., and that there will be a minimum number of external pipes, inasmuch as inlet and exhaust manifolds are within the block cylinder casting, the multiple water return pipe heretofore commonly used being dispensed with in favor of a single-short pipe connected between the forward end of the engine and the radiator.

Various modifications and changes may be made in the specific construction described without departing from the scope of the invention.

The novel features of inlet and exhaust manifolds herein shown but not claimed, are claimed in my copending application Serial No. 523,554, filed December 17, 1909, while the novel features of gearing for driving the auxiliaries are claimed in Patent No. 1,146,788, issued July 20, 1915, upon application Serial No. 759,627, filed April 8, 1913, as a division hereof, while novel features herein disclosed pertaining to an inclosed combustion engine are claimed in another copending divisional application hereof, Serial No. 759,628, filed April 8, 1913.

Having thus described my invention, I declare that what I claim as new and desire to secure by Letters Patent, is—

1. The combination with a multiple cylinder engine casting comprising at least four cylinders and a water jacket cast integrally and having a water inlet adjacent one end, of a removable longitudinal cover for closing the water jacket having a water discharge outlet, said cover being adapted to fit the casting in such manner as to bring said discharge outlet at the same end of the casting as said water jacket inlet, and means within the water jacket for causing a portion of the cooling water to flow longitudinally of the casting over the cylinders before reaching said cover discharge.

2. In a multiple cylinder engine, a plurality of cylinders, a water jacket for said cylinders open at the top, an inlet opening adjacent one end of said jacket, and a cover for said jacket having a water passage therein opening outwardly at the end adjacent said inlet opening, and inwardly at the opposite end.

3. The combination in a multiple cylinder engine casting comprising cylinders and a water jacket cast integrally, of a water inlet at one end and a water outlet at the opposite end, and baffle plates within said jacket and between said inlet and outlet for distributing and directing the flow to the various cylinders.

4. The combination in a multiple cylinder casting comprising closed cylinders and a water jacket open at the top cast integrally, of a water inlet at one end into the water jacket, a cover separable from the casting for closing the water jacket and having a passage therethrough opening to the end of the water jacket opposite the inlet end.

5. The combination in a multiple cylinder engine casting comprising closed cylinders and a water jacket open at the top cast integrally, of a hollow cover for said water jacket having a longitudinal water passage therethrough, one end of said water passage opening into the water jacket at one end and outwardly at the other end.

6. In a multiple cylinder engine casting, a plurality of cylinders, an integral water jacket surrounding said cylinders and having a water inlet at one end, a cover for said jacket spaced above the cylinders receiving the flow therefrom at the other end of said casting, and having a discharge outlet at its opposite end.

7. A casting for a multiple cylinder explosion engine comprising at least four cylinders, an inlet for each cylinder, a manifold inlet pipe integral with the cylinders and connected to said inlets, a cooling jacket outside said cylinders and manifold having a water inlet adjacent one end, and a removable cover for said jacket receiving the flow therefrom at the other end of the casting and having a discharge outlet at its opposite end.

8. A casting for a multiple cylinder explosion engine comprising at least four cylinders, an inlet and an exhaust for each cylinder, manifold inlet and exhaust pipes integral with the cylinders and connected respectively to said inlets and exhausts, a cooling jacket outside said cylinders and manifolds having a water inlet adjacent one end, and a removable cover for said jacket receiving the flow therefrom at the other end of the casting and having a discharge outlet at its opposite end.

9. A casting for a multiple cylinder explosion engine comprising at least four cylinders, an inlet and an exhaust for each cylinder, manifold inlet and exhaust pipes on one side of said cylinders and integral therewith connected respectively to said inlets and exhausts, a cooling jacket outside said cylinders and manifolds having a water inlet adjacent one end of said exhaust manifold, and a removable cover for said jacket receiving the flow therefrom at the other end of the casting and having a discharge outlet at its opposite end.

10. The combination in a multiple cylinder engine casting comprising cylinders and a water jacket cast integrally, of a water inlet at one end and a water outlet from the jacket at the opposite end, and means within

4
said jacket for intermediately dividing the flow of water into a plurality of substantially parallel vertical streams, whereby water of substantially the same temperature 5 flows about each of said cylinders between said inlet and outlet.

11. A water jacketed engine casting comprising a plurality of parallel cylinders having integral heads, a water jacket surrounding said cylinders and heads, a water inlet adjacent one end and a water outlet adjacent the other end, and means between each cylinder and the jacket for directing the flow of water upwardly of said cylinders and longitudinally over said cylinder heads to said outlet. 10

12. A water jacketed engine casting comprising a plurality of parallel cylinders having integral heads, a water jacket surrounding said cylinders and heads, a water inlet adjacent one end and a water outlet adjacent the other end at different levels, and means between each cylinder and the jacket for directing the flow of water upwardly of said cylinders and longitudinally over said cylinder heads to said outlet. 15

13. In a multiple cylinder water jacketed engine casting, a plurality of parallel cylinders having integral heads spaced within said jacket, a water inlet adjacent one end of the casting, means for causing the water from said inlet to flow upwardly in parallel streams over each cylinder and merge in a stream flowing in the space over the tops of said cylinders, and a discharge outlet at the top of the opposite end of said casting, whereby convection assists the water flow. 20 25

14. In a multiple cylinder water jacketed

engine casting, a plurality of parallel cylinders having integral heads spaced within 40 said jacket, a water inlet adjacent one end of the casting, means comprising vertical baffles for causing the water from said inlet to flow upwardly in parallel streams over each cylinder and merge in a stream 45 flowing in the space over the tops of said cylinders, and a discharge outlet adjacent the top of the opposite end of said casting, whereby convection assists the water flow.

15. In a multiple cylinder water jacketed 50 engine casting, a plurality of parallel cylinders having integral heads spaced within said jacket, a water inlet adjacent the bottom of said water jacket at one end of the casting, means comprising vertical baffles between said jacket and cylinders and between certain of said cylinders for causing the water from said inlet to flow upwardly in parallel streams over each cylinder and merge in a stream flowing in the space over 55 the tops of said cylinders, and a discharge outlet at the top of the opposite end of said casting, whereby convection assists the water flow. 60

16. In a multiple cylinder engine casting, 65 integral cylinders and heads, a water jacket inclosing said cylinders, an inlet and an exhaust valve chamber for each cylinder on one side of said casting within said water jacket, inlet and exhaust gas passages within said 70 water jacket and below said valve chambers, and valve stem guides formed in said casting between said inlet and exhaust gas passages.

In testimony whereof I affix my signature, in presence of two witnesses.

GUIDO FORNACA.
